Bennington Gill of New York City.
Letters Patent

The Schedule referred to in the Letters Patent and making part of the same containing a description in the words of the said Bennington Gill himself of his improvement in the Cooking Stove.

To all to whom these presents shall come, Know ye that Bennington Gill of the City, County and State of New York have invented contrived and applied to use a new and useful improvement in a cooking Stove, called "Gill's improved cook Stove", which improvement and the Stove wherein it is made is described as follows, namely. For the bottom of the Stove I make a circular plate of Iron C (see drawings) ten feet six inches in diameter and of suitable thickness, which plate I raise from the ground about five inches by feet D (see drawings) sliding into dovetails on the under side of it. upon the centre of this plate I place a cast iron Box E (see drawings) ten inches square closed on three sides and open on one side for the admission of the drawer F (see drawings) to contain the ashes. this drawer is four and one half inches deep and nine and one half inches wide. On the inner surfaces of the right and left sides of this box I cast projecting G (see drawings) with hollow upon the upper part, for the admission of the ends of the axle of the revolving and falling gate described below. This Box is sometimes cast permanently with the circular plate forming the bottom of the stove, and sometimes cast separately and confined to its place by rods passing thro' its cover and the plate secured by nuts below. Upon the above described projecting on the interior sides of the Box, I place the axle H (see drawings) of a circular grate I (see drawings) which axle is fastened to the grate by a pin passing through the centre of the grate and a projecting part K (see drawings) of the axle. The projecting part is two inches in length and the grate is seven and three quarters inches in diameter, and revolves freely round the pin which attaches it to the axle. On the under side of the grate I cast two dovetails each extending from the edge of the centre to the rear part on the side of it and back about three inches leaving a triangular slit

opening between them to receive the shaking pin P. (see drawings.) This pin I make of thin soft steel, not rounded, flattened at one end and with a loop on the other. Upon the ^{front} ~~front~~ ^{back} side described I place the cover L which is a plate eleven inches square having a circular aperture in the center eight inches in diameter in which the circular grate moves, and having near the front edge a projecting part M (see drawings) on the lower side one inch wide and nine and a half inches long extending down to meet the front of the ash drawn. In this projecting part of the cover I make an oblong hole O (see drawings) about three inches long & half an inch wide, through which it passes the shaking pin into the slit between the door tails, under the grate with the flattened end in a vertical position in which way it will pass through the slit until the flattened end jets beyond the door tail, when I turn the pin so as to bring the flattened end into a horizontal position which it cannot be drawn out being prevented by the narrowing of the passage between the door tails. Upon this cover I place a cylinder Q (see drawings) seven and three quarter inches in diameter at bottom and twelve inches top and seven inches high. This is the chamber of combustion, holding the fuel and having the circular grate at bottom. Upon the top of this cylinder I place the receiver R (see drawings) which is twenty four inches diameter at bottom, twenty four and three quarter inches at top and five inches inches deep, having a circular aperture in the center twelve inches in diameter, fitting the top of the cylinder through which the heat and smoke ascend into the receiver. Across this circular aperture and immediately over the cylinder separating from each other those parts of the boiler holes which extend over the cylinder I place a partition S. (see drawings) made of iron fire brick, soap stone or other suitable material having flanges on the lower edges to receive the dampers or slides T. (see drawings) and having one of its ends forked to facilitate the action of the valve V (see drawings.) These dampers or slides are made to shut over that part of the circular aperture which is under either of the boiler so that by opening the proper valve and closing the others, the whole current of the fire from

The air may be directed in the first instance under a particular boiler, while by the action of the vertical valve described below, the heat and smoke are compelled to pass around the receiver and every or all the other Boilers at will. On the inner side of the boiler, in sections, are pairs of cast iron guides, U. (see drawings,) about three eighths of an inch high, extending from the points where the partitions are, upon the bottom of the receiver back to the inner side of it so as to regulate the action of the dampers as they are moved backward and forward. In the damper I affix rods, N. (see drawings,) passing through the rim of the receiver with baf^s, or other balls on the outer ends, about one inch from the union of the rod with the damper I make a joint in the rod which permits it when the damper is drawn back, to fall into a pendent position on the outside of the receiver. On one side of the receiver and opposite to the forked end of the partition I make an oval opening W. (see drawings,) and an oval collar for the attachment of the pipe. On each side of the opening and attached to the inner side of the rim of the receiver are projections, X (see drawings,) about one inch wide, extending from the bottom to the top of the receiver, against which the vertical valve shuts as it is moved in either direction. This valve extends from the partition to the outer edge or rim of the receiver and is made to move in a vertical position in the groove formed at the frise of the partition, so that when shut against either of the above described projections it shuts out the passage of the heat and smoke from the receiver to the pipe in that direction. On the top of the Receiver, I place I place the cover Y (see drawings,) a circular plate fitting by a groove around to the receiver in which are holes to admit the cooking utensils, if any, which holes when not occupied by the cooking utensils are covered by girdles, Z. (see drawings,) the vertical valve is moved by a handle attached to a part of it projecting through the cover of the receiver, by which valve the draft can be made to pass around the top of the other or receiver and Boilers in it from right to left or from left to right at pleasure. or I place a permanent partition nose off from the side of the receiver to the inner partition and dispense with

the vertical ovens. The stove above described is intended for burning coal. When wood is to be used for fuel the form of the chamber of combustion and lower parts of the stove are altered, but the receiver is the same as above described, and the flame and smoke ascend into it in the same manner, nor through the circular aperture in the bottom. I perform baking & and roasting in all or either of the following ways. 1° By an iron oven in the rear of the chamber of combustion, round which I cause the fire to circulate before it is admitted into the receiver above.

2° By tin or other reflectors placed under the receiver and in front or at the sides and back or around the chamber of combustion, &c. 3° By tin or other iron & reflectors placed upon the top of the receiver. The form of the Receiver of the Boiler, and the Boiler holes, of the partition within the receiver and the valves may be varied, but in all cases in such manner that the direct communication between the chamber of combustion and the bottom of each boiler may be shut off at pleasure by valves operating either by sliding horizontally or vertically or turning upon an axis or in any other mode that the form adopted for the Boiler holes & receiver may render expedient. By which means as will be seen by reference to the model a great economy of fuel is effected. The heated air in its course to the chimney is so directed as to pass under the bottom of all the Boilers and at the same time effectually to warm the ovens, while valves so command the direct heat from the fire that a greater or less portion can be had at pleasure for each or any Boiler without disturbing or deranging the action of the heat upon any other Boiler or upon the oven. A comparison of this model with any stove previously made will show its excellency. The top or receiver may be square or circular as in the model and drafts or angles may be hexagon or an octagon or any other convenient form and may with the other parts of the stove be varied in size to suit the purchaser, taking care to preserve the proportions. The drawings annexed will show more accurately the form of the parts and to them reference is made.

The part of the above described stove in which my improvement is made is the top or that part which is above the fire place or chamber for

the fuel and which I have called the Receiver, and it consists in the new arrangement, above described in a stationary top of the stove so as effectually to distribute and guide the heat when generated to the objects, for which it is wanted in such proportions of in such times & in such manner as may be required. This is effected by arranging the cooking utensils or vessels over the fire as above described, & by providing the horizontal slide, movable to close in part or whole as may be needed, the aperture, through which the flame & heat ascend and by means of the perpendicular valve or other fixture or nozzle the smoke pipe or outlet of the top for the purpose of giving direction to the flame and heat and the internal arrangement & construction of the above described parts in and upon the top of the stove, the whole being combined in such a manner as to produce the desired result. I claim as, my invention and improvement, the construction arrangement and combinations of the above described parts comprising the interior of the top of said stove and any other similar arrangement & combination of similar parts for the same purpose placed over the fire in the top of a stove for the purpose aforesaid and for this improvement I request Letters Patent.
